UNITED STATES PATENT OFFICE.

ALBERT H. NELLER, OF MAPLETON, MINNESOTA.

CORD-CUTTING KNIFE FOR GRAIN-BINDERS.

SPECIFICATION forming part of Letters Patent No. 699,553, dated May 6, 1902.

Application filed February 26, 1901. Serial No. 48,924. (No model.)

To all whom it may concern:

Be it known that I, ALBERT H. NELLER, a citizen of the United States, residing at Mapleton, in the county of Blue Earth and State 5 of Minnesota, have invented a new and useful Cord-Cutting Knife for Grain-Binders, of which the following is a specification.

My invention is an improved revoluble cord-cutting knife for grain-binders of the McCormick type, the object of my invention being to effect improvements in the construction of the knife, whereby the binding-cord is prevented from prematurely coming in contact with the cutting edge of the knife pending the operation of the knot-forming mechanism and the binding of the gavel.

To this end my invention consists in a revoluble cord-cutting knife for grain-binders and a guard revoluble with the knife and extending in advance of and above the cutting edge thereof and adapted when the binding-cord is laid to keep the cord out of contact with the cutting edge of the knife between the binder-arm and the cord-holder.

25 In the accompanying drawings, Figure 1 is a perspective view of a cord-cutting knife embodying my improvements, showing the same in operative relation to the knotting mechanism of a McCormick grain-binder.

30 Fig. 2 is a detail perspective view of my improved cord-cutting knife. Fig. 3 is a detail elevation of the same.

The revoluble knife 1 comprises the central circular plate 2, the upturned blades 3 at opposite sides thereof having the oppositely-disposed cutting edges 4 and provided on their upper sides with guards 5, which project in advance of and over the said cutting edges. The knife, as is usual, is attached to 35 the lower side of the usual cord-holder *a* of a McCormick binder, as described in Letters Patent of the United States No. 442,544, and revolves therewith.

Heretofore the knife has not been provided 45 with the guards 5, and in the operation of the grain-binder, when the binding-cord *b* is by the binder-arm *c* disposed over the cord-holder, over the finger *d*, and in position to be caught by the knotter-bill *e*, the cord, during the formation of the gavel and just prior 50 to the operation of the knotting mechanism,

has been disposed in advance of one of the cutting edges of the knife, with the result that at times the cord comes prematurely in contact with the cutting edge of the knife, is 55 cut thereby, and consequently a bundle is not tied, hence rendering the operation of the binding and knot-forming mechanism imperfect and uncertain in this particular. To obviate this defect, I provide my improved 60 knife with the guards 5, which are disposed above and project forward over the cutting edges 4 of the knife. At each semirotation of the knife with the cord-holder one of the guards 5 of my improved knife is disposed 65 in line with the binding-cord *b*, as the same is by the binder-arm *c* disposed in the position shown in Fig. 1, and the binding-cord is caught by the guard, the binding-cord resting on the guard and the latter serving to 70 keep the cord from coming in contact with the cutting edge 4 of the knife, as shown in Fig. 1. Hence the binding-cord cannot be prematurely cut by the knife, and the operation of the machine in the formation, binding, and tying of the gavels is rendered cer- 75 tain.

The operation of the binding, knotting, and cutting mechanism is well understood by those skilled in the construction and operation of the McCormick grain-binder, and hence is not stated here, and only so much of the mechanism of the McCormick grain-binder is here shown as is needful to illustrate the operation of my improved knife in connection therewith. 80

My improved knife is set back on the cord-holder about an inch as compared with the knife shown and described in the patent hereinbefore mentioned, the relative positions of 90 my knife and the cord-holder being such that the foremost cutting edge 4 of the knife is in the rear of the cord when the latter is laid, with the guard projecting forward from said cutting edge and disposed under the cord, 95 hence effectually keeping the latter from premature contact with a cutting edge of the knife at a point between the binder-arm and the cord-holder.

I find by experiment that not only is my improved knife provided with the guards above and in advance of the cutting edges effective 100

in preventing the premature cutting of the binding-cord, but that my knife, by reason of its being set back with relation to the cord-holder, enables the machine to tie a much 5 tighter knot than formerly, the guards serving to keep the binding-cord from contact with the cutting edges, while the movement of the cord-holder is effective in tightening the knot.

10 Heretofore the tension of the cord between the cord-holder and the binder-arm or the initial disposition of the cord in rear of the foremost cutting edge of the knife has been relied upon to prevent the occasional premature cutting of the cord. Both of these expedients are, however, ineffective. By providing the knife with the guards herein described I obviate this difficulty. Hence the cord may be somewhat slack between the cord- 15 holder and the binder-arm without coming in premature contact with the knife, as the guard would keep it from the edge of the knife, and hence the springs on the cord-holder and knotter-bill may be weakened, as 20 before stated.

I also find by experiment that in the practical operation of the machine the springs on the cord-holder and also on the finger of the knotter-bill do not need to be so tightly ad- 25 justed as formerly and do not require to be of such strength as has heretofore been nec- essary.

Having thus described my invention, I claim—

1. A revoluble cord-cutting knife for grain-binding machines having a guard in advance of and above the cutting edge thereof to prevent the cord from prematurely coming in contact with the cutting edge of the knife at a point between the binder-arm and the cord- 40 holder, substantially as described.

2. A revoluble cord-cutting knife for grain-binding machines, comprising a central plate, upturned blades each having a cutting edge, said cutting edges being reversely disposed 45 and guards disposed above and projecting in advance of the said cutting edges, substantially as described.

3. In a machine of the class described, the combination of a cord-holder, a revoluble 50 knife, and a guard, revoluble with the knife and extending in advance of and above the cutting edge thereof, said guard being adapted when the cord is laid, to keep the cord out of contact with the cutting edge of the knife, 55 between the binder-arm and the cord-holder, substantially as described.

In testimony that I claim the foregoing as my own I have hereto affixed my signature in the presence of two witnesses.

ALBERT H. NELLER.
